UNITED STATES PATENT OFFICE

139,023

DESIGN FOR AN AIR GAUGE

Leonard R. Mehlman, Chagrin Falls, Ohio, assignor, by mesne assignments, to Jack & Heintz, Inc., Cleveland, Ohio, a corporation of Ohio

Application January 31, 1944, Serial No. 112,389

Term of patent 14 years

(Cl. D52—1)

To all whom it may concern:

Be it known that I, Leonard R. Mehlman, a citizen of the United States, residing at Chagrin Falls, in the county of Cuyahoga and State of Ohio, have invented a new, original, and ornamental Design for an Air Gauge, of which the following is a specification, reference being had to the accompanying drawing, forming part hereof, wherein:

Figure 1 is a front perspective view of an air gauge showing my new design; and

Figure 2 is a rear perspective view.

I claim:

The ornamental design for an air gauge, substantially as shown.

LEONARD R. MEHLMAN.
